OIL BURNER

William H. Link, San Diego, Calif.

Application December 27, 1941, Serial No. 424,659

4 Claims. (Cl. 158—66)

My invention relates to an oil burner, more particularly to a burner for burning different types and grades of fuel oil and the objects of my invention are:

First, to provide an oil burner of this class which is adjustable throughout so that it is applicable for use in connection with burning various types or grades of fuel oils or fluids;

Second, to provide an oil burner of this class with a novel vaporizing means;

Third, to provide an oil burner of this class with novel air inlet damper means;

Fourth, to provide an oil burner of this class which is particularly arranged to be positioned in the ordinary lid opening of a wood or coal burning stove;

Fifth, to provide an oil burner of this class which may be easily taken apart for cleaning the same if desired;

Sixth, to provide an oil burner of this class in which all of the parts and portions are relatively adjustable;

Seventh, to provide an oil burner of this class which is very simple and economical of construction, easy to operate, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a top or plan view of my oil burner complete; Fig. 2 is a side elevational view thereof and Fig. 3 is an enlarged sectional view taken from the line 3—3 of Fig. 1 showing some of the parts in elevation to facilitate the illustration.

Similar characters of reference refer to similar parts and portions throughout the several views of the drawings:

The supporting housing 1, adjustment spider 2, fuel inlet conductor 3, air damper 4, vaporizing members 5, 6 and 7, and housing 8 constitute the principal parts and portions of my oil burner.

The supporting housing 1 consists of a disk-like plate portion 1a which is adapted to fit into a conventional stove lid opening, as shown by dash lines in Fig. 3 of the drawings. This plate 1 is provided with a large central opening 1b and between this central opening and the periphery is provided an upwardly extending annular

housing portion 1c which is preferably integral therewith as shown best in Fig. 3 of the drawings.

Positioned on the upper edge of the portion 1c of the member 1 is an adjustment spider 2. This spider member 2 is provided with three extended finger members in the preferred form as shown best in Fig. 1, but may have more if desired. It is provided centrally with an upwardly extended hub portion 2a which is screw threaded at 2f to be screw-threaded on the threads 3a of the fuel inlet conductor 3, all as shown best in Fig. 3. This fuel inlet conductor 3 is a pipe-like tubular member provided with threads 3b at its upper end adapted to receive the threads of a conductor for the fuel oil from any supply, not shown. Screw-threaded on the thread 3a of the member 3 is the hub portion 4a of the air damper 4. This air damper 4 is a disk-like member which is adapted to rest over the opening 1b in the member 1 and may be raised and lowered relatively thereto by means of the threads 4b in the hub portion 4a on the thread 3a of the member 3. This damper member 4 is provided with a plurality of air inlet openings 4c through which 20 the air passes downwardly into and around the vaporizer consisting of the members 5, 6 and 7.

The vaporizer member 5 is provided with an upwardly extending hub portion 5a which is screw-threaded with threads 5b which are adapted to fit the lower ends of threads 3a, it being noted that the thread 3a on the member 3 extends from the lower end to past the upper side of the hub 2a, as shown best in Fig. 3 of the drawings. This hub portion 5a is provided 30 with lateral ports 5c which permit the fuel oil to pass outwardly as shown by arrows in Fig. 3. The main portion 5d of the member 5 is a relatively thin disk-like member so that it heats quickly to provide quick vaporization to facilitate the lighting of the burner.

The periphery of the member 5d rests on a flange portion 6a of annular nut 6, as shown best in Fig. 3. This member 6 is provided with threads 6b which are screw-threaded on threads 7a on the lower edge of the annular member 7 which forms the side wall for the vaporizer consisting of the members 5, 6 and 7. This member 7 extends upwardly some distance to near the lower side of the opening in the member 1a. The blaze from the burner extends from near the upper inner side of the member 7 over the upper edge and outwardly as shown by arrows in Fig. 3. Inasmuch as the vaporizer consisting of the members 5, 6 and 7 is secured on the lower end of the member 3, it will be noted that by

turning the adjustment spider 2 on the member 3, the vaporizer member may be raised and lowered and held in such raised or lowered position, also the damper member 4 may be raised and lowered relatively to the opening 1b by turning the same on the member 3.

Secured to the lower side of the supporting housing 1 and extending around the vaporizer consisting of the members 5, 6 and 7 is the vaporizer housing 8 which is provided with a substantially semi-spherical cup-shaped member 8a at its lower side which is integral with a disk-like portion 8b which is provided with a relatively large central opening 8c in which the vaporizer member is centralized. This portion 8b is provided at its periphery with an upwardly extending flange portion 8d. This member 8 is supported by means of three upwardly extending lugs 8e which are secured to the member 1 by means of screws 8f. Thus the vaporizer housing 8 is rigidly secured in such relation with the supporting housing 1.

The operation of my oil burner is substantially as follows: Fuel oil in regulated quantities passes down the interior of the inlet conductor 3 and passes outwardly through the openings 4c into the vaporizer as shown by arrows in Fig. 3. Air passes downwardly around the members 2b, 2c and 2d into the member 1c and through the openings 4c in the damper 4 contacting the fuel oil vapor in the upper part of the vaporizer portion 7 forming mixed fuel in the upper portion of this vaporizer member 7 which is ignited between the members 8e by a match, or otherwise. Any particle of the fuel oil not burned will go into the cup shaped member 8a and will be later burned and utilized. In order to properly adjust the air flow and vaporizer position, the spider 2 may be turned to raise the fuel inlet conductor 3 upwardly toward the air stream passing through the openings 4c. At the same time the damper member 4 will be raised from its seat admitting air all around the outside. This damper member may be turned by placing a pointed instrument between the members 2b, 2c or 2d and into one of the openings 4c and turning the member 4 on the fuel inlet conductor 3 while the vaporizing member remains stationary, thus providing for the burning of various gravity fuels and various quality fuel oil.

Though I have shown and described a particular construction, combination and arrangement of parts and portions, I do not wish to be limited to this particular construction, combination and arrangement but desire to include in the scope of my invention the construction, combination and arrangement substantially as set forth in the appended claims.

Having thus described my invention, what I claim as new and desire to secure by Letters Patent is:

1. In an oil burner of the class described, the combination of a supporting housing open at its

upper side and provided with a limited opening at its lower side, a spider resting on the upper open side of said housing, a tubular fuel inlet conductor adjustably mounted in said spider, a cup-like vaporizer member secured on the lower end of said fuel inlet conductor and communicating with said fuel inlet conductor, and a damper member provided with a plurality of openings therethrough adjustably mounted on said fuel inlet conductor over said limited opening in said supporting housing.

2. In an oil burner of the class described, the combination of a supporting housing open at its upper side and provided with a limited opening at its lower side, a spider resting on the upper open side of said housing, a tubular fuel inlet conductor adjustably mounted in said spider, a cup-like vaporizer member secured on the lower end of said fuel inlet conductor and communicating with said fuel inlet conductor, a damper member provided with a plurality of openings therethrough adjustably mounted on said fuel inlet conductor over said limited opening in said supporting housing, and a housing positioned around the lower portion of said vaporizer member.

3. In an oil burner of the class described, the combination of a supporting member provided with an annular upwardly extending wall and also provided with a central opening, a vaporizer supporting member supported on said annular wall and arranged to be revolved thereon, a fuel inlet conductor adjustably mounted in said vaporizer supporting member, a damper member adjustably mounted on said fuel inlet conductor positioned over the opening in first mentioned supporting member and a vaporizer mounted on said fuel inlet conductor in spaced relation from said damper, said vaporizer including an annular vertical member, a bottom therefor and a nut arranged to secure said bottom in connection with said annular member.

4. In an oil burner of the class described, the combination of a supporting member provided with an annular upwardly extending wall and also provided with a central opening, a vaporizer supporting member supported on said annular wall and arranged to be revolved thereon, a fuel inlet conductor adjustably mounted in said vaporizer supporting member, a damper member adjustably mounted on said fuel inlet conductor positioned over the opening in first mentioned supporting member and a vaporizer mounted on said fuel inlet conductor in spaced relation from said damper, said vaporizer including an annular vertical member, a bottom therefor, a nut arranged to secure said bottom in connection with the first mentioned annular member and a housing member supported by said supporting member and enclosing the lower side of said vaporizing member and spaced therefrom.

WILLIAM H. LINK.
